CLAIM

The ornamental design for a beard mask, as shown and described.

DESCRIPTION

FIG. 1 is a perspective view of a beard mask showing my new design;

FIG. 2 is a perspective view of FIG. 1 being shown in a used condition on a human figure shown in broken lines;

FIG. 3 is a front view of FIG. 1;

FIG. 4 is a back view of FIG. 1;

FIG. 5 is a right side view of FIG. 1;

FIG. 6 is a left side view of FIG. 1;

FIG. 7 is a top view of FIG. 1; and,

FIG. 8 is a bottom view of FIG. 1.

The broken line showing of a human figure are included for the purpose of illustrating unclaimed environment and form no part of the claimed design.

1 Claim, 5 Drawing Sheets(56)
